ROLLING DEVICE FOR SCRUBBING, &c.

1,348,683.

Specification of Letters Patent.

Patented Aug. 3, 1920.

Application filed February 3, 1920. Serial No. 355,903.

To all whom it may concern:

Be it known that we, HERBERT G. ALDENBRUCK and LEONARD E. WEBBER, citizens of the United States, residing at St. Paul, in 5 the county of Ramsey and State of Minnesota, have invented a new and useful Rolling Device for Scrubbing, &c., of which the following is a specification.

Our invention relates to means for facilitating the scrubbing of floors and base boards, and the object is to provide a truck riding on casters and adapted to carry in 10 kneeling position the person doing the scrubbing, and also to carry a pail of water 15 or soap suds and the brush and rags used for scrubbing. Other objects will be stated in the description of the operation of the device.

In the accompanying drawing:

20 Figure 1 is a plan view of the device with a water pail placed upon it. Fig. 2 is an edge view or elevation of Fig. 1. Fig. 3 is a bottom view of the device.

Referring to the drawing by reference 25 numerals, 4, 4^a are two members of the main platform, they are each secured by screws 5 upon one of two bars 6, the free ends of which extend in opposite directions one in under each adjacent platform member and 30 is there secured by a bolt 7 having thumb-nut 8 and which is removable to different holes 9 in the bars, so as to thereby alter the width of the platform.

The platform is provided in its top with 35 grooves 10 for the knees and legs of the operator, and the under side is provided with four casters, 11, of such height that the toes of the operator will bear but lightly on the floor 12.

40 The right and left edges of the platform are provided with eyes 13, and with a recess 14, in which is fixed a headed stud 15.

The scrub pail 16 is supported on a secondary platform, 17, having a guard 18, and 45 at its bottom a cleat 19, to which is fixed a single caster 20. The inner edge of the platform 17 is supported by hooks 21 hooked downwardly into the eyes 13, and by a hook

or catch 22, pivoted at 23 and adapted to engage the stud 15 when the platform 17 is 50 at the right hand side of the operator, and may engage the stud 15^a if the operator is left handed so he puts the platform 17 at the left side, where its hooks 21 will engage in the eyes 13^a. Such changing of the platform 17 may be unnecessary if the grooves 10 be made open at both ends, but it is believed to be preferable to have their front 55 ends closed by terminals or margins 24 so as to limit the forward movement of the 60 knees of the operator.

In the operation of the device the scrub pail 16 is placed on the platform 17, where it is guarded from sliding by the guards 18 and by the cleats 18^a. Scrub-brush, wash-rag, wiping rag, and soap or washing powder may be placed on the platform near the pail. The operator now kneeling on the platform does the washing or scrubbing in 65 about the same way as an operator kneeling 70 on the floor or on a piece of board placed on the floor, but instead of rising up and carrying the pail from place to place and kneeling again and getting wet and dirty on the floor, the operator simply touches the floor 75 or baseboards sufficiently to move the truck on which he or she and the pail and tools are supported, from one place to another in any desired direction until the work is done.

The device is also handy for painters to 80 use in oiling, varnishing or painting floors and baseboards.

And when the device is not in use for the purposes stated, it can be used by children as a kiddy-car, one child sitting or standing 85 on the main platform and propelling it forward by hand or foot movement, and a smaller child may have a ride on the platform 17. In this capacity the device may be used either in the house or on porches 90 and side-walks.

The device is provided with a brake composed of a press-button 25 supported by a spring 26 and having a vertical stem 27, 95 slidable in the main platform and provided with a brake shoe 28. The latter is adapted

to contact with the floor or sidewalk as the case may be whenever the operator presses the button 25.

What we claim is:

5. In a device of the kind described, a platform mounted on casters and having its top provided with parallel grooves adapted to receive the knees and legs of a kneeling person; said platform composed of two sec-

tions connected together and arranged for separation more or less apart, the grooves being two in number and arranged one in each section.

In testimony whereof we affix our signatures.

HERBERT G. ALDENBRUCK.
LEONARD E. WEBBER.
